UNITED STATES PATENT OFFICE.

CHRISTEN SEEBERG, OF OSLO, NORWAY.

SKI BINDING.

Application filed January 25, 1927, Serial No. 163,320, and in Norway February 8, 1926.

My invention relates to a ski binding of the kind in which the toe part of the foot is fastened by aid of clamping members gripping the edge of the boot sole.

5 The object of my invention is to provide clamping members of this kind, swingingly connected to the rigid toe lugs themselves or to members hinged thereto, in such manner as to ensure an efficient clamping pressure, against the edge of the sole, allowing simultaneously the clamping member to roll along the rim of the sole without diminishing its clamping pressure, in such manner as to avoid undue strain on the interconnection between boot and sole.

In the accompanying drawings three different forms of the invention are illustrated.

Figs. 1 and 2 are a transverse sectional view and side view, respectively, of one form of the invention, and

20 Figs. 3 and 4 corresponding views of another form.

Fig. 5 is a sectional view of a third form.

Referring now to Figs. 1 and 2, 1 is one 25 of the rigid side lugs fastened to the ski, and 3 the clamping member clamping the edge of the boot sole to the ski, swinging thereby about a bolt 2 on the outer side of the rigid lug 1, parallel to the same, the 30 curved clamping face 4 being bent at right angles to the rest of the clamping member and extending inwards through a slot 5 arranged below the bolt 2 in the rigid toe lug 1. The sole of the boot is indicated in 35 broken lines. It will be understood that the same arrangement is duplicated on the other side of the ski.

In the form illustrated in Figs. 3 and 4 the clamping piece is likewise on the outside of the lug 1, but the bolt 2 serving as its 40 swinging fulcrum here is placed below the slot 5, and not above as in the preceding form, but this arrangement makes it necessary to make the curvature of the clamping 45 face of a somewhat smaller radius than in the preceding form in order to enable it to roll along the edge of the sole during the up and down movement of the latter.

In the executional form illustrated in 50 Fig. 5 the clamping members 6 are not attached direct to the rigid lugs 1, but to the clamping arms 7, which are interconnected by strops and attached to the rigid lugs

1 by aid of hinges as known from U. S. Patent No. 1,113,496, the swinging clamping 55 members 6 being substituted for the rigid clamping lugs known from said patent. In order to enable the adjustment of the swinging clamping lugs 6 in conformity with the thickness of the projecting rims of the soles, 60 the arms 7 are provided with two or more holes 9, into which the swinging bolt 8 of said clamping lugs may be inserted, according to the thickness of the sole. The clamping members 6 are illustrated as arranged 65 on the inner side of the arms 7, but they may also if desired be placed on the outside of said arms, with their clamping faces inserted through slots as explained for Figs. 1 to 4.

Claims:

1. In ski bindings having the toe part of the foot fastened to the foot by aid of clamping means gripping the edges of the boot soles, said clamping means being 75 fastened to the rigid toe lugs of the skis, the arrangement of clamping members turnably mounted on said rigid toe lugs and having curved clamping faces adapted to roll along said sole edges. 80

2. In ski bindings having the toe part of the foot fastened to the foot by aid of clamping means gripping the edges of the boot soles, said clamping means being fastened to the rigid toe lugs of the skis, the 85 arrangement of clamping members turnably mounted on said rigid toe lugs and having curved clamping faces adapted to roll along said sole edges, said clamping members being suspended on the outside of said rigid 90 toe lugs and reaching inwards through slots in said lugs with their curved clamping faces.

3. In ski bindings having the toe part of the foot fastened to the foot by aid of 95 clamping means gripping the edges of the boot soles, said clamping means being arranged on clamping arms hinged to the rigid toe lugs of the ski, the arrangement of clamping members turnably suspended on 100 said clamping arms and having curved clamping faces adapted to roll along said sole edges.

In testimony whereof I have signed my name to this specification.

CHRISTEN SEEBERG.
